MANUFACTURE OF STRUCTURAL MATERIAL

1,071,718.

Specification of Letters Patent.

Patented Sept. 2, 1913.

Application filed March 10, 1911. Serial No. 613,622.

To all whom it may concern:

Be it known that we, CHARLES E. DUNCAN, residing at Sault Ste. Marie, Province of Ontario, and Dominion of Canada, and JOSEPH FAWELL, residing at Pittsburgh, in the county of Allegheny and State of Pennsylvania, citizens of the United States, have invented or discovered certain new and useful Improvements in Manufacture of Structural Material, of which improvements the following is a specification.

As is well known to those skilled in the art, the lower flange of an I beam or other structural shape when arranged horizontally on separated supports, forms the most important element in sustaining the load and that such portion of the flange which is farthest from the neutral axis of the beam *i. e.* the lowermost portion of said flange, will be subjected to the greatest strain. Hence in the manufacture of the beams care should be taken that no flaws or defects are produced in that portion of the flange and that the metal should not be put under injurious strains.

Two forms or types of mills are now generally used in the manufacture of beams, etc. The first consists of two high or three high rolls having grooves progressively varying in contour and dimensions. As is well known to those skilled in the art the reducing or shaping surfaces formed by the walls of the grooves vary greatly in peripheral speed, especially if the flanges to be formed, are wide. By reason of the difference of rate of movement of portions of the reducing surfaces from that of the article between the rolls and the fact that the rate of movement of the walls of the grooves which shape the flanges, differs most greatly from the rate of movement of the article, the metal of the flanges is subjected to great strains and there is a tendency to tear the metal thereby forming cracks in the surfaces of the flanges, especially the outer surfaces due to the grinding and tearing action when the reducing surfaces slip along the gradually stiffening metal. In the other form or type of mill, generally known as a universal mill, consisting of horizontal and vertical rolls, the rolls are adjustable to effect the required variation of dimensions of the pass, between back and forth passes between the rolls. In this mill the opera-

tive surfaces of the horizontal rolls are so shaped as to impart to the article while the web is being reduced to gage, the required contour to the inner faces of the flanges. In other words the horizontal rolls are formed with collars having cross-sectional shape and dimensions corresponding to the portion of the beam within the flanges. These collars displace the metal vertically to form the web of the beam. The sides of the collars do not effect any substantial lateral displacement of the metal, they simply serve as internal support for the metal which is to form the flange while the latter are being shaped and brought to size by the vertical rolls, which are adjusted inwardly toward each other after each pass. In thus rolling the beam the largest periphery of the horizontal rolls will have the highest peripheral speed and the rate of movement of the article through the rolls will be approximately the same. But the peripheral speed of the sides of the collars is slower proportionately to their distance from the axes of the rolls and hence these surfaces will tend to have a retarding effect on the metal adjacent thereto. The vertical rolls, which operate on the outer faces of the flanges, will unless positively driven have a peripheral speed approximately equal to that of the article between the rolls. It will be readily understood that as the metal in contact with the sides of the collars must be dragged along by the conjoint pull of tops of the collars and the vertical rolls, there will be a constant tendency to tear the metal, producing cracks transverse of the direction of movement of the article. These cracks, if formed, are closed up and not visible, and even if not formed the tearing action of the rolls will have a weakening effect. This weakening of the web and the inner faces of the flanges does not seriously affect the beam, but the weakening of the outer faces of the flanges when the beam is so placed that one of the flanges will be in tension, is believed to be detrimental.

The invention described herein has for its object the production of a structural shape in such manner that the outer faces of the flanges will be substantially free from cracks or injurious strains.

The invention is hereinafter more fully described and claimed.

In the accompanying drawing forming a part of this specification, Figure 1 shows in elevation a stand of universal rolls for the practice of our invention; Fig. 2 shows diagrammatically the positions of the vertical rolls in successive stands for the practice of our invention and Fig. 3 is a diagrammatic view showing the successive reductions effected in rolling a blank down to 10 a finished beam.

In the practice of our invention, the ingot is broken down in a blooming or universal mill and partially shaped. During this operation, reduction is effected at all points 15 without any injury to the metal as it is so hot and plastic as to readily yield and flow under the pressure of the rolls without any tendency to tear. As the reduction continues the portions which go to form the 20 flanges become thinner and cooler and the metal less plastic, so that in subsequent reductions the change of shape is due mainly to flow under pressure and to some extent to a tearing of the metal, producing cracks 25 and strains. At about the time or preferably just before the metal reaches this critical temperature, which will be readily recognized by the skilled rollers, the blank is reduced to or approximately to the depth 30 (the distance between the points *a*—*a* in the drawing), required in the finished beam, so that no further working or reducing action of the outer faces of the flanges is required while portions of the blank between planes 35 coinciding with the outer faces of the flanges is being reduced.

While for reasons hereinafter stated it may be desirable to progressively change to small extent the depth of the blank such 40 change is not due to any reduction or working of the metal of the outer faces of the flanges. The blank having been reduced to or approximately to the desired depth at about the time stated in subsequent operations 45 the depth is changed if at all by a stretching of portions of the metal between the finished outer faces of the flanges. At this time the blank will have a contour substantially similar to that indicated by the 50 full lines in Fig. 3 and all subsequent reduction should be within planes coinciding with the outer faces of the flanges. These reductions may be effected in a two high or three-high mill having grooves or passes 55 formed therein suitable for the progressive reduction of the blank or in a universal mill in which the vertical rolls, having been adjusted a distance apart equal or substantially equal to the desired depth of the beam, 60 will not be substantially changed during reduction. While the desired reduction may as stated be effected in a universal or a two high mill, it is preferred to employ a universal mill of the type shown and claimed 65 in the application of Joseph Fawell filed

February 3rd, 1911, Serial No. 606417 in which the blank is reduced in a series of fixed passes each formed by two horizontal and two vertical rolls. When employing this mill the dimensions of the operative portions of the horizontal rolls are changed for each pass as indicated by dotted lines in the drawing. In addition to changes in dimensions here will be also such slight changes in contour as are required to properly shape the portions of the beam within 70 the flanges and the inner faces of the flanges. 75

It will be observed that in each pass a reduction of the web portion and also of the thickness and width of the flange portions 80 of the blank is effected but that the relative positions of the outer faces of the flanges are not materially changed. As no material change of depth is effected, the outer faces of the flange will in a two high mill simply 85 slide along the reducing faces of the rolls to an extent equal to the difference of speed of the article and the roll faces; and the same is true when a universal mill is employed but not to so great extent, hence 90 there will not be any tendency to so tear the metal as to produce cracks or strains.

It will be readily understood by those skilled in the art, that if the vertical rolls 4 of successive passes or stands of rolls, are 95 arranged the same distance apart as for example twenty-four inches, some positively acting means will be necessary to cause the article to enter successive passes. In order to avoid the use of such feeding device we 100 prefer to arrange the vertical rolls of successive passes a little farther apart. As for example if rolling a twenty-four inch beam the first pass for the blank would have the vertical rolls arranged a little less distance 105 than desired in the finished beam but slightly greater, an eighth of an inch more or less than the depth of the blank to be fed into such pass. With such a difference between the depth of the beam and the distance 110 between the vertical rolls the blank will readily enter and when subjected to the reducing action of the horizontal rolls 3, will be spread until its flange faces are supported by the vertical rolls as shown in Fig. 115 1. In the next pass or stand of rolls, the vertical rolls 5 are arranged a little farther apart, say an eighth of an inch more or less, than the rolls 4 as clearly indicated in Fig. 2. In all the successive stands or passes the 120 vertical rolls are arranged a greater distance apart than in the preceding pass or stand, the distance between such rolls 12 in the last or finishing pass being equal to that desired in the finished article. It will be 125 observed that in this method of rolling the vertical rolls do not effect in and of themselves a reducing action which is accomplished by the horizontal rolls as before stated. The vertical rolls simply serve as 130

anvils or supports to hold the flanges in position to be acted on by the horizontal rolls. In Fig. 3 the dotted line *a* indicates the dimensions and contour of the blank and the lines *b*, *c*, *d*, etc., indicate the shapes and dimensions produced in successive passes. It will be observed that in lieu of the vertical rolls acting to reduce the transverse dimensions of the blank in directions parallel or approximately parallel with the web, there is a small progressive increase in depth and that the outer faces of the flanges of the beam are outside of the finish line of any of the preceding passes. This small and gradual change is not due to any reducing action of the vertical rolls on the flanges but to a gradual progressive transverse stretching of the metal of the web by the wedging in action of the collars on the horizontal rolls. So far as reduction is concerned the flanges are finished externally in the last pass of the blooming or blanking mill or in the first pass of the finishing mill as before stated.

We claim herein as our invention:

1. The method herein described of manufacturing structural material, which consists in reducing in successive passes an ingot or billet in one direction, approximately to its final transverse dimension and partially reducing portions of the ingot or billet, in other directions, reducing in closed passes such partially shaped portions to final dimensions, and during such reduction permitting an increase of said transverse dimension.

2. The method herein described of manufacturing structural material, which consists in forming a blank having a depth less than that desired in the finished article, reducing such blank to the finished article and

changing the depth of the blank by predetermined increments while so reducing.

3. The method herein described of manufacturing structural material, which consists in forming a blank by reducing an ingot or billet in all directions, the reduction in one direction being approximately to finished dimensions, finishing the blank by reduction within the planes of the extremities of said finished dimension and during such reduction, increasing by predetermined amounts, the dimensions of the approximately finished portion.

4. A plant for rolling structural material, having in combination a series of stands of rolls, each consisting of a pair of horizontal and a pair of vertical rolls, the vertical rolls of successive stands being arranged a sufficiently greater distance apart than those of the preceding stand as to permit the free entrance of the material between the vertical rolls.

5. A plant for rolling I-beams, having in combination a series of stands of rolls provided with reducing passes increasing progressively in depth or the distance between the faces of the passes operative on the outer faces of the flanges as to permit the entrance of the material into successive passes.

In testimony whereof, we have hereunto set our hands.

CHARLES E. DUNCAN.
JOSEPH FAWELL.
